UNITED STATES PATENT OFFICE

THOMAS L. YOUNG, OF SEATTLE, WASHINGTON

ROLL PAPER DISPENSER

Application filed August 8, 1927. Serial No. 211,564.

The invention is a coin control machine for dispensing sheets of paper of predetermined lengths from a roll.

The object of the invention is to provide a machine for dispensing predetermined lengths of paper or the like which may be manually operated and which may be released by a coin so that it will dispense one length of paper only, by one coin.

10 Another object of the invention is to provide a dispensing apparatus which is normally locked and which may be released to dispense a predetermined length of paper by inserting a coin therein.

15 A further object of the invention is to provide a dispensing apparatus which may be operated only after a coin has been inserted and which may continue to be operated until a predetermined amount of material has 20 passed therethrough after which it will automatically lock.

25 And a still further object of the invention is to provide a manual control dispensing apparatus which is of a simple and economical construction.

With these ends in view the invention embodies a roller upon which a roll of paper may be mounted, feed rollers for feeding the paper from the roll, gears cooperating 30 with the said feed rollers and operable by a crank, and suitable locking means for the said gears which may be released by inserting a coin in the device.

Other features and advantages of the invention will be seen from the following description taken in connection with the drawings wherein,

35 Figure 1 is a view looking at one end of the device with the end plate omitted and 40 showing the operating gears in the locked position.

Figure 2 is a similar view showing the operating gears released and the locking means in the position at which the coin is 45 released.

Figure 3 is a front view of the device with part of one end broken away to show the location of the operating device.

In the drawings the device is shown as 50 it would be made wherein numeral 1 indi-

cates a roll of paper, numeral 2 the main operating gear and numeral 3 the coin chute.

The roll of paper 1 is mounted upon a shaft 4 which is held in slots 5 in end plates of the casing. The paper from the roll passes 55 downward between two feed rollers 6 and 7 as shown. One of these rollers may be made of metal with small corrugations in the surface as shown in Figure 2 and the other may be made of wood or any other suitable material. It is also understood that either of these rollers may be made of any other suitable material and their surfaces formed in any suitable manner so that they will grip and feed the paper. The roller 7 is mounted 60 upon a shaft 8 in a slotted hole 9 and is resiliently held against the roller 6 by a spring 10 as shown. The roller 6 is mounted upon a shaft 11 and at one end of this shaft is a crank 12 by which the roller may be 65 rotated. This shaft 11 is provided with a gear 13 that meshes with the main operating gear 12.

The gear 2 is rotatably mounted on a pin 14 and is provided with a lug 15 as shown. It 75 will be observed that the lug 15 engages the end of a lever 16 which is pivotally mounted on a pin 17 and which extends into the coin chute 3. The lever 16 is also held by a connecting arm 18 through a pin 19 in a slotted 80 opening 20 in the arm and the opposite end of the arm is pivotally connected to the main gear 2 through a pin 21. It will be observed that as a coin in the chute engages the end of the lever 16 it will move this end of the lever 85 downward to position shown in dotted lines in Figure 1 and move the opposite end of the lever upward so that it will be above the lug 15 so that the gear 2 may rotate in a counter-clockwise direction and may therefore be 90 rotated by the crank. As the gear continues to rotate the arm 18 will move the end of the lever 16 upward to the position shown in Figure 2 and at the same time the opposite end of the lever 16 will move downward and release 95

the coin. A latch 22 is also provided which is pivotally mounted on a pin 23 and arranged to engage the teeth of the gear 2 to prevent the gear rotating backwards or in a clockwise direction.

- It is understood that changes may be made in the construction without departing from the spirit of the invention. One of which changes may be in the general design or arrangement of the casing, another may be in the use of other means for feeding the paper, another may be in the use of other means for controlling the feeding means and still another may be in the use of other means for locking the said controlling means.
- 5 The construction will be readily understood from the foregoing description. To use the device it may be provided as shown and it will be observed that normally it will be impossible to operate the crank 12 to turn the device in either direction, however when a coin is placed in the chute 3 it will raise the inner end of the lever 16 and thereby release the lug 15 so that the crank may be turned in a clockwise direction to dispense the paper. As the device continues to be operated the arm 18 will raise the end of the lever 16 to release the coin and then as the operation is continued the arm 18 will move downward to the position shown in Figure 1 and the lug 18 will engage the end of the lever 16 so that the device will again assume a locked position.
- 10 15 20 25

Having thus fully described the invention what I claim as new and desire to secure by Letters Patent, is:

30 In a device of the class described, a coin chute, a pivotally mounted horizontal lever with one end extending into the coin chute, said end extending into the chute adaptable to engage and hold a coin passing through the said chute and adaptable to be moved slightly downward by the weight of the coin, a gear, a shaft upon which the said gear is mounted, a lever eccentrically attached to the said gear and having a slotted opening through which it is attached to the horizontal lever, said lever being adaptable to raise the horizontal lever and release the coin as the gear is rotated, a stop on the said gear adaptable to engage the end of the said horizontal lever, a pawl adaptable to engage the teeth of the said gear to prevent its rotating in a reverse direction, a suitable casing, and means for rotating the said gear from the outside of the casing.

35 40 45 50

In testimony whereof I affix my signature.
THOMAS L. YOUNG.
